UNITED STATES PATENT OFFICE.

JOHN T. HAWKINS, OF TAUNTON, MASSACHUSETTS.

CYLINDER PRINTING-PRESS.

SPECIFICATION forming part of Letters Patent No. 257,579, dated May 9, 1882.

Application filed April 18, 1881. (No model.)

To all whom it may concern:

Be it known that I, JOHN T. HAWKINS, of Taunton, in the county of Bristol and State of Massachusetts, have invented a new and useful Improvement in Cylinder Printing-Presses, which improvement is fully set forth and illustrated in the following specification and accompanying drawings.

The objects of this invention are the same as those set forth in connection with a summary of the state of the art in the specifications of my inventions in printing-presses here-with filed, and respectively marked cases A and B; but the distinctive characteristic of this invention is that the sheet is delivered tail first from the cylinder, instead of head first, by means of certain combinations of devices, which will now be described, as follows:

In the said drawings, Figure 1 illustrates 20 in side elevation a cylinder-press containing the improvements constituting this invention. Fig. 2 is a rear elevation of the machine illustrated in Fig. 1, having the feed-board and fly-board omitted. Fig. 3 is a plan of the machine 25 with the feed-board and ink-rollers omitted. Fig. 4 illustrates in two views enlarged details of certain parts shown in Figs. 1 and 2, and hereinafter fully described. Fig. 5 illustrates a rear elevation of the cylinder of the press, 30 showing certain details of construction hereinafter described.

In the said figures the same parts are indicated by like letters, as follows:

The letter A indicates the side frame of the 35 machine; B, the impression-cylinder; C, the feed-board; C', the fly-board; R, the ink-rollers; B', the bed; G, a crank secured to a shaft, G', to be driven by any suitable means or power.

To the crank G is secured the crank-pin c , 40 which by the connecting-rod c' is connected to the shaft P', which serves as the axis or journal of the rolling pinion P.

The stationary rack E is secured to the bed 45 or roller-ways R² of the framing of the machine, and a corresponding rack, E', is attached to the under side of the reciprocating bed of the press B', to and between which racks the rolling pinion P is geared and rotates.

Journaled within the roller-frame or carriage 50 K are a series of rollers, E², which are secured

to shafts S S, as is likewise secured the pinion P to the shaft P', journaled in the said frame or carriage.

The rollers E² revolve and traverse within 55 the roller-ways R² and support the bed B' by its corresponding roller-ways, R³. This arrangement gives to the bed a rectilinear motion or length of travel double that imparted to the carriage K, thus avoiding the use of a 60 crank of inconvenient length or too great radius. The rack R⁴ is secured to the upper side of the bed B', to which is geared the gear-wheel R⁵, secured to the impression-cylinder B.

The cam D upon the shaft G', through the 65 intervention of the roller D', connecting-rod D², crank-arm D³, eccentric rock-shaft D⁴, and cylinder-journal side rods, D⁵, raises and lowers the cylinder B to clear the types or form at the proper time.

The cam F upon the shaft G', through the 70 intervention of the roller F, connecting-rod F², crank-arm F³, rock-shaft F⁴, the two attached lever-arms F⁵, and returning-springs F⁶, imparts a reciprocating motion to the slides F⁷ 75 upon the guides F⁸. The guides F⁸ have their ends fixed in the standards S', secured to the frames A. The slides F⁷ carry two shafts, V³ V⁴, respectively provided with two lower jaws, g and g', forming two sets of traveling grippers. 80

The upper jaws, g', and their shaft V⁴ have 85 no other motion than that due to the reciprocation or travel of the slides F⁷; but the lower jaws, g, in addition to the same reciprocation, are caused to open and close for the purpose of seizing the sheets between or releasing them from said jaws at the proper times. The grippers g g' are thus operated. The lower jaws, g, are kept shut by means of the helical spring V⁵, coiled around their shaft V³; but when in the 90 course of delivery of the sheet the small curved lever-arm V², likewise secured to the shaft V³, is brought in contact with the roller V' upon the bracket V it causes a partial rotation of the shaft V³, and consequently the depression and opening of the jaw g, which opening releases the sheet from the grippers g g', whence it falls upon the fly-board below.

As the grippers leave the roller V they are again closed by the spring V⁵, and so remain until, at the other end of their travel, the jaws g are again opened by the arm V⁶, loosely

mounted upon the shaft V^3 , coming in contact with the pin p , secured in the standard S' , which contact causes said arm to rise against the pin p' in the curved arm V^2 , thereby turning the shaft V^3 and depressing the jaw g , thus opening the grippers for the insertion of the leading edge of the sheet. At this time the slides F^7 have approached the cylinder and are nearly though not quite at rest. The loose arm V^6 therefore just passes over the pin p before the slides reverse, thereby releasing the jaw g , so that it is instantly closed upon the upper jaw, g' , thus holding the sheet between said jaws by the reaction of the helical spring V^5 .

15 The shaft b extends across the press at the back of the cylinder, and is journaled in the frames A . Secured to said shaft is a series of bridge-fingers or strippers, b' , and a crank-arm, b^2 , is also secured to said shaft outside of 20 the frame A , as shown at the right hand of Fig. 2.

To the crank-arm b^2 is articulated a connecting-rod, b^3 , the lower end of which is connected to one of the cylinder-journal side rods, D^6 , by 25 a pin, b^4 , by means of which connection the reciprocating motion of the side rods, D^6 , is transmitted to the bridge-fingers or strippers b' , which are thus caused to approach the cylinder B as it rises and to recede from it as it 30 is lowered by the successive operations of the cam D and the side rods, D^6 , and their connections, already described.

The bridge-fingers or strippers b' are so adjusted on the shaft b that when the cylinder B 35 and its side rods, D^6 , are raised said fingers and the brushes journaled therein, as herein-after described, just escape contact with the blanket or tympan surrounding the cylinder-surface, while with the cylinder B lowered down 40 and printing, said fingers, with their brushes, are carried far enough away from the cylinder to clear the sheet thereon.

In and through the bridge or stripper fingers b' is journaled a small shaft, h , carrying 45 a series of narrow rotary brushes, h' . The shaft h is driven from a pulley, h^2 , upon the cylinder's axis by means of a belt, h^3 , leading to an idler-pulley, h^4 , upon a stud in the frame A , and thence by a belt, h^5 , to a pulley, h^6 , upon the end of the brush-shaft h , all of which 50 is omitted in Fig. 2 for the sake of clearness of illustration. By this means the shaft h and its brushes h' are carried by the strippers b' away from the cylinder B , to clear the sheet 55 during the printing rotation of the cylinder, and caused to approach it at the commencement of the retrogression. Hence it is quite obvious that the revolution of said brushes will raise the tail of the sheet upon the strippers b' as the cylinder commences to retrograde. The cylinder then continues to deliver the sheet upon said strippers during the whole 60 of its retrogression. The cylinder and brushes are shown in detail in Fig. 5.

65 A small shaft, j , (not shown in Fig. 2,) is journaled in the frames A , and carries two or more

narrow pressure-rollers, j' , which are so placed thereon as to run or revolve on the unprinted margins of the sheet. Said rollers are adjusted to bear lightly upon the sheet while it 70 is passing under them, yet cause sufficient friction between the cylinder-surface or tympan and the sheet to insure the carrying backward of the sheet by the cylinder B during its retrogression.

75

The complete operation of the machine is as follows: The sheet being fed by the usual guides from the feed-board C , is taken thence to the cylinder-grippers just as the cylinder is brought almost and practically to rest by the 80 arrival of the crank G at its dead-center. Correct feeding-register is thus assured, all these parts being then in a state of least motion. The crank G , then passing its center, commences to move the bed upon its forward or 85 printing stroke. The bed, thus put in motion, causes the cylinder to rotate forward and carry the sheet through the process of receiving the impression, the cam D through its connections, already described, having at the commencement 90 of said rotation of cylinder and printing-stroke of bed lowered the cylinder B into contact with the form and held it there during the stroke just described.

The diameter of the cylinder B and the 95 stroke of the bed B' are so proportioned each to each that the cylinder is caused to make a greater rotation than one complete revolution during a single stroke of the bed, sufficient to bring the tail of a full-sized sheet above the 100 points of the oscillating bridge-fingers or strippers b' .

At the conclusion of the printing-stroke just described the cam D , through its connections already described, brings the bridge-fingers or 105 strippers b' close enough to just clear the surface of the cylinder B or tympan covering it as it retrogrades, and causes the brushes h' , journaled in said strippers, to press lightly upon the cylinder's surface. The tail m of the 110 sheet is thus elevated from the cylinder's surface by the revolving action of the brushes h' , and by them lifted above the bridge-fingers b' , which latter then strip the sheet from the cylinder at the commencement of its retrogression. The traveling grippers $g g'$, through the operation of the cam F , formed and adjusted as described, are now caused to approach the cylinder, to seize the tail m of the 115 sheet as it passes upon the bridge-fingers b' , and to carry the sheet backward over the fly-board C' at about the same velocity with which it is delivered by the cylinder B upon said bridge-fingers, and then to release the sheet and drop it upon the fly-board C' , or upon the 120 previously-delivered sheet, by the sheet's own gravitation, at or near the termination of the grippers, backward travel, as or when the curved lever V^2 comes in contact with the roller V' , as above described.

130 In the drawings the feed-guides and all devices or means for operating the cylinder-grip-

pers and ink-rollers have been omitted, as such means form no part of this invention, and may be adopted in any of the usual forms or modes of arrangement best suited to the particular 5 form of press or kind of work required.

I do not confine myself to the methods shown for oscillating the bridge-fingers or strippers *b'*, for raising and lowering the cylinder *B*, or for imparting motion to the traveling grippers 10 *g g'*, as all of said movements may be effected in many well-known ways, as may be most suitable to the kind and proportion of press desired.

The inherent advantages of this machine due 15 to its construction and mode of operation, briefly enumerated, are as follows: The sheets are delivered from the top of the cylinder, the tail of each sheet first upon a series of oscillating bridges or stripper-fingers during the 20 retrogression of the cylinder, and are thence taken and delivered by a series of traveling grippers to and upon the fly-board, which, as well as the grippers, occupies a position at the back of the press under the feed-board. The 25 machine thus simply constituted is of comparatively inexpensive design and very durable. By means of its arrangement of parts herein described it is capable of producing the finest kinds of printing without marring the same by 30 subsequent contact of the work with parts of the delivery mechanism, and this without the use of cords, tapes, or strings in the delivery of the sheets. Each sheet is delivered in an even pile upon the fly-board with its last printed side upward in full sight of the pressman. 35 These results are attained with a smaller diameter of cylinder at a much higher rate of speed of press than can be obtained with those presses involving the use of buffers or buffer-springs, stop-cylinders, or cylinders continuously revolving in one direction only, all necessity for the use of any of which means or 40 methods is in this machine entirely avoided.

I am aware that it is not new to rotate the cylinder in one direction only for making the 45 impression and in the reverse direction during the retrogression of the reciprocating bed of the press, the cylinder being driven directly by the bed, and such method, *per se*, I do not claim; but

As of my invention I claim—

1. In a cylinder printing-press, a delivery cylinder, a series of oscillating stripper-fingers provided with rotary brushes and reciprocating or traveling sheet-grippers, in combination with means, substantially as described, for transmitting motion to said parts, each movement being so timed in relation to the others that each sheet is delivered tail first from the back and top of the cylinder upon 60 said stripper-fingers, and thence seized and the delivery of the sheet completed by said grippers, substantially as and for the purposes set forth.

2. In a cylinder printing-press, in combination with a reciprocating bed and an impression-cylinder and geared to said bed so as to make a greater rotation than one complete revolution of the cylinder to one stroke of the bed in each direction, a series of oscillating 70 stripper-fingers provided with rotary brushes, and reciprocating or traveling sheet-grippers situated at the back of the cylinder, substantially as and for the purposes set forth.

3. In a cylinder printing-press, in combination with its cylinder, a series of oscillating or vibrating sheet stripper-fingers, a series of rotary brushes, and means, substantially as described, for imparting motion to said parts, whereby the edge of each sheet is elevated and 80 stripped from the cylinder, substantially as set forth.

JOHN T. HAWKINS.
